UNITED STATES PATENT OFFICE.

JAMES W. IVORY, OF PHILADELPHIA, PENNSYLVANIA.

DENTAL MULTIPLE-JAW CERVIX-CLAMP.

1,265,664.

Specification of Letters Patent.

Patented May 7, 1918.

Application filed December 18, 1917. Serial No. 207,654.

To all whom it may concern:

Be it known that I, JAMES W. IVORY, a subject of the King of Great Britain, residing in the city and county of Philadelphia, 5 State of Pennsylvania, have invented a new and useful Dental Multiple-Jaw Cervix-Clamp, of which the following is a specification.

My invention consists in providing a dental cervix clamp with a plurality of interchangeable auxiliary jaws adapted for different purposes, as for instance, one for ordinary cervical cavities, and others, rights and lefts for cavities that extend around and between the teeth on either side, they being adapted to fit the juncture of the bow of the clamp and are easily changeable, providing also for the attachment of jaws of other patterns.

20 The invention is satisfactorily illustrated in the accompanying drawings, but the important instrumentalities thereof may be varied, and so it is to be understood that the invention is not limited to the specific details shown and described, as long as they are within the spirit or scope of the claims.

Figures 1 and 2 represent elevations of opposite sides of a dental multiple jaw cervix clamp embodying my invention.

30 Fig. 3 represents an elevation at a right angle to Fig. 1.

Fig. 4 represents a longitudinal section of the clamp.

Fig. 5 represents an elevation of the bow of the clamp having thereon a member embodying my invention.

Fig. 6 represents an elevation of a bow having thereon an auxiliary jaw, and the attaching device therefor embodying my invention.

Fig. 7 represents a perspective view of said jaw and device.

Fig. 8 represents a section thereof on line 8-8 Fig. 7.

5 Fig. 9 represents a transverse section of a portion on line 9-9 Fig. 2.

Figs. 10 and 11 represent elevations of jaws for right and left purposes.

Figs. 12, 13 and 14 represent elevations of 0 different forms of auxiliary jaws that may be employed, Fig. 13 being at a right angle to Fig. 12.

Similar numerals of reference indicate corresponding parts in the figures.

Referring to the drawings.

1 designates the bow of a dental cervical

marginal clamp, and 2 and 3 designate jaws thereof mounted slidably on the frame of the clamp which jaws with other features, and the operating mechanism of the movable 60 members are in general respects the same as shown in the dental cervical marginal clamp for which Letters Patent of the United States, No. 1,032,833, were granted to me on the 16th day of July, 1912.

To the terminals of said bow as shown in said patent there is attached the outwardly extending tongue 4 which forms a juncture for said terminals on what comprises the crown of the bow which is adapted to support different forms of separate interchangeable auxiliary jaws 5, as will be hereinafter described.

In Fig. 6 I show one of said jaws, it being of segmental shape and standing out from the base of a sleeve 6 which may be fitted on the tongue 4 and so supported, said sleeve having connected therewith the resilient finger 7 forming a spring which is adapted to bear against said tongue 4 and so by friction retain the sleeve and consequently the jaw 5 on said tongue.

In the base of the tongue 4 is the recess 8 into which the terminal of the spring 7 is seated so as to assist in retaining the sleeve 85 6 with its jaw 5 steadily and firmly in position on the tongue 4.

In Figs. 10 and 11 the jaws are made respectively right and left. In Figs. 12, 13 and 14 the jaws are of lengths or breadths different from those shown in Figs. 6, 10, and 11.

It will be seen that owing to the jaws employed on the bow the clamp is adapted to meet any condition that would appear in the class of cavities in teeth. The jaws are 95 made narrow or broad for ordinary cervical cavities, and rights or lefts for cavities that extend around and between the teeth on either side.

Jaws of other patterns are adapted to be 100 employed and attached to the tongue 4 and held in position thereon.

It will be seen that I employ three jaws each independent of the other. When the clamp is applied, the jaw on the bow is carried in position above the cavity or margin by the operation of the proper screw of the bow, the force being sure but being exerted gradually. When the clamp is placed on the tooth but not drawn too taut, the labial 105 110 jaw must be capable of moving. Then the edge of the rubber that is around the tooth

should be raised so that it rests on the arm at the top of the labial jaw before forcing the jaw into position above the cavity. This keeps the rubber out of the way and prevents it from being torn. When the clamp is in place and made secure the rubber is slipped from said arm.

The tongue 4 forms a junction of the heretofore separated terminals of the bow and comprises an apex for the bow preventing spreading of the latter. The sleeve 6 and the spring 7 are formed preferably integral, said sleeve as is evident being open from below, whereby it may be readily fitted on the tongue and removed therefrom.

Another important feature of the present invention is the employment of the finger pieces 9 which project laterally from opposite sides of the shank of the jaw 3, the same providing connecting means for easily and uniformly manipulating and adjusting said jaw in its relative position on the labial face of the tooth.

Having thus described my invention what I claim as new and desire to secure by Letters Patent, is:—

1. An auxiliary jaw for a dental cervix clamp composed of a jaw proper, and a sleeve-like body carrying the same, said body being adapted to be fitted on a member of the clamp.
2. In a dental cervix clamp having a bow, a tongue on the crown of the latter forming a support for a separate auxiliary jaw.
3. An auxiliary jaw for a dental cervix

Copies of this patent may be obtained for five cents each, by addressing the "Commissioner of Patents, Washington, D. C."

clamp consisting of a jaw proper and a sleeve-like body carrying the same, said body being adapted to be fitted on a member of the clamp, and a device on said body adapted to engage said member to retain it thereon.

4. In a dental cervix clamp having a bow, a separate auxiliary jaw, and a tongue on said bow for the attachment of said jaw thereto.

5. A dental cervix clamp having a bow, and means for primary connection of the clamp with a tooth, and a separate auxiliary jaw attachable to said bow beyond said means.

6. In a dental cervix clamp, separate interchangeable auxiliary jaws either of which is adapted to be mounted on a member of said clamp and provided with means for securing it in position thereon.

7. An auxiliary jaw for a dental cervix clamp having a bow, a sleeve-like member carrying said jaw, and a resilient device on said member, said member being adapted to be mounted upon said bow, and said device being adapted to frictionally engage said bow.

8. In a dental cervix clamp, a jaw slidably mounted on the frame thereof, and finger pieces on opposite sides of the shank of said jaw projecting laterally therefrom.

JAMES W. IVORY.
